UNITED STATES PATENT OFFICE.

CHARLES J. GUTBERLET, OF PHILADELPHIA, PENNSYLVANIA.

PYRALINE DOCUMENT-HOLDING ENVELOPE.

Application filed December 31, 1923. Serial No. 683,833.

The pyraline document holding envelope, has the two walls formed from one piece of sheet pyraline folded crosswise at the bottom of the envelope. One of these two side walls has retaining flaps that are folded over the outside of the other side wall, and yielding hold the latter near its edges and leave it free to slide sidewise between them and the inside of the side wall that they are attached to. The inside edges of the flaps bear against the outside of the wall of the envelope which they hold. Folding the envelope from a single sheet with the two side walls folded at the bottom of the envelope positions these walls so that the narrower side wall will lie always centrally on the other and its edges draw out equally from beneath the flaps. As pyraline is an exceedingly resilient material, this construction will result in a greatly enlarged capacity and in the contents of the envelope being held firmly between the side walls whether much or little is contained in the envelope.

Fig. 1 is a side elevation of the document holding envelope. Fig. 2 is an edge elevation thereof. Figs. 3 and 4 are sections on lines 3 and 4 respectively of Fig. 1. Fig. 5 a section on line 5—5 of Fig. 1. Figs. 6, 7 and 8 are illustrations of a step of the process. Figs. 6 shows it with a side elevation of the envelope; Fig. 7 with a section on line 3—3 of Fig. 1 of same, and Fig. 8 a view of the envelope looked at from the top.

Pyraline is a transparent stiffish material; when cold it is highly resilient, and not pliable. A sheet of it, if bent, will spring back and become flat repeatedly and with considerable force and resists strongly being permanently bent, although it yields readily and bends temporarily, but tending always to spring backwards and to exert a pressure against the deforming material.

1 and 4 are the two side walls of the pyraline document holding envelope. One of these walls has the flaps, 2, 2, that fold over a portion near each of the edges of the wall 4. The edge, 5, of these flaps, 2, 2, which lies towards the middle line of the envelope (see particularly Fig. 5) lies close to the outer face of the wall 4, and the curve of the fold, 6, has diameter large enough to leave quite a space between the flaps, 2, 2, and the wall 1, near the fold. This enables the wall, 4, to be substantially as wide as the wall, 1, without any danger that its

edges will stick in the pocket between the flap, 2, 2, and wall, 1. The fold, 7, between the walls, 1 and 4 extends the entire width of the envelope, and positions the wall, 4, 60 exactly over the wall, 1. The stiffness of the pyraline walls, 1 and 4, makes this position positive, and their resiliency brings them back to its original flat shape. The clamping effect of the flaps, 2, 2, upon the 65 wall, 4, is exerted at a point at or near the inner edges of the flaps. The effect of inserting any documents into the envelope is to make the edges of the side wall, 4, slide away from the bottom of the pockets formed 70 between the flap, 2, 2, and the wall (away from the folds, 6). These movements, on account of the length of the fold, 7, and the stiffness of the pyraline walls, will be equal, and the inner edges of the flaps, 2, 2, by 75 lying close against the wall, 1 will hold the edge of the wall 4 against the wall, 1, until the edges of the wall, 4, are withdrawn from beneath the flaps, 2, 2. This gives great 80 holding capacity to the envelope and the resiliency of the two sheets, 1 and 4 clamped together, as above described, will hold the documents, whether a few or a large number, very firmly, so that they will not slip out even if the envelope should be reversed or 85 fall a distance.

The folds, 6, are made in a manner that produces the fullness above described at the bottom of the pocket between the flaps, 2, 2, and the wall, 1. 20, 20, is a pair of rollers 90 turned by a handle, 21. Each roller is provided with a rubber blanket, 22. The pyraline is softened by heating and passed through the rollers, 20, 20. The folds, 6, being started the rollers will press down the 95 inner edges of the flaps, 2, 2, more than the parts of them near the folds, 6. This is because the fold will offer a greater resistance to the pressure and will sink more deeply into the rubber blanket. This will produce the fullness at the bottom of the pockets between the flaps, 2, 2, and the wall, 1, and the close clamping pressure of the inner part of the flaps, 2, 2, on the inside of wall, 1.

I claim—

1. A document holding envelope of sheet pyraline, the two side walls of the envelope being formed of a single sheet folded at the bottom of the envelope and one of the side walls being provided with flaps folding over 110 toward the inner side of the side wall of the envelope to which they are attached and

forming pockets between them and this wall, in which the outer edges of the other wall fit and in which they slide freely, the said flaps holding their position entirely by the 5 resiliency of the pyraline fabric, and their turned over portions being free from the wall of the envelope to which they are attached, and being entirely free from and

unattached to the wall of the envelope inserted in the pockets formed by these flaps. 10

2. The device, as described in claim 1, with this element additional:—the pockets being wide at the fold between the flap and the wall to which it is attached and contracted at the inner edges of the flaps.

CHAS. J. GÜTBERLET.
